UNITED STATES PATENT OFFICE.

THOMAS F. LARKIN, OF NEW YORK, N. Y.

DESIGN FOR A SACRAMENTAL CANDLE.

56,441.

Specification for Design.

Patented Oct. 26, 1920.

Application filed March 13, 1920. Serial No. 365,666. Term of patent 14 years.

To all whom it may concern:

Be it known that I, THOMAS F. LARKIN, a citizen of the United States, residing at New York, in the county of New York and State of New York, have invented a certain new, original, and ornamental Design for a Sacramental Candle, of which the following is a specification.

This invention has relation to sacramental candles, and has for an object to provide a new, original and ornamental design therefor, of which the following is a specification.

In the drawings;

Figure 1 is a view in perspective of my new, original and ornamental design for a sacramental candle.

Fig. 2 is a view thereof in side elevation, and

Fig. 3 is a view thereof in bottom plan.

The candle, as shown is substantially cylindrical with grooved or fluted sides, and formed at the top with a dome terminating in an annular ridge centrally located. An opening extends through the candle in which a wick is placed. The body of the candle may be yellow and the wick purple.

Having thus described my invention, what I claim as new and desire to secure by United States Design Letters Patent is:

The ornamental design for a sacramental candle as shown.

In testimony whereof I affix my signature.

THOMAS F. LARKIN.
